(57) **CLAIM**

The ornamental design for a drying rack, as shown and described.

DESCRIPTION

FIG. 1 is a front, right and top perspective view of a drying rack, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a half-open state view thereof;

FIG. 10 is a storage state view thereof;

FIG. 11 is an enlarged view of portion of FIG. 1 thereof;

FIG. 12 is an enlarged view of portion of FIG. 2 thereof; and, FIG. 13 is an enlarged view of portion of FIG. 9 thereof.

The broken lines shown in the drawings illustrate portions of the drying rack that form no part of the claimed design. The dot-dash broken lines depict the boundaries of the enlargements that form no part of the claimed design.

1 Claim, 13 Drawing Sheets
